TOOTH BRUSH RETAINER

Benjamin Oshman and Joseph Oshman,
New York, N. Y.

Application March 6, 1936, Serial No. 67,498

1 Claim. (Cl. 312—112.5)

This invention relates to a tooth brush retainer, and its objects are to retain the brush efficiently in convenient location, to maintain it clean, dust-proof, sanitary, and out of contact with other articles, and to provide improved means for its rapid, ready, and convenient withdrawal from the container and reinsertion thereinto.

Other objects and advantages will hereinafter appear.

10 In the accompanying drawing,

Fig. 1 is a longitudinal cross-sectional elevation of the tooth brush retainer of this invention.

Fig. 2 is a rear elevation of the container shown in Fig. 1.

15 Fig. 3 is a front elevation of a part of the container.

Fig. 4 is a transverse-sectional plan view of the container, taken on the line 4—4 of Fig. 1.

20 Fig. 5 is a longitudinal cross-sectional end elevation showing a modification of the invention.

Fig. 6 is a front elevation showing the retainer adapted for a plurality of tooth brushes.

The tooth brush 1, Fig. 1, used in connection with the retainer 2 of this invention, has its handle portion 3 near its brush head 4 preferably specially configurated, as by a pair of opposite notches 5 and symmetrical curvings 6, Fig. 3. Said retainer has a box like receptacle 7, which is elongated to conform with the shape of the brush head 4, and comprises side walls 8, an end wall 9, and a bottom or rear wall 10, while its forward end 11 is configurated to register with the notches 5 and curvings 6, providing a narrow opening 12 in forward wall 13 with an open tray-like extension 14, as shown, whereby the brush head 4 may be inserted in the receptacle by lowering or moving it laterally thereinto, with the notches 5 embracing the wall portions 13 and the handle portion 3 being embraced by the curved sides 15 of extension 14. When so inserted in the receptacle 7, longitudinal movement or removal of the brush will be prevented by the above registration of the forward end 11 with the portion 3 of the brush handle. The receptacle 7 is longitudinally slideable into and out of a container 16 comprising side walls 17, front and rear walls 18, 19, and an end wall 20. Rear wall 19 is provided with a projection 21 constituting a bracket for securing the container 16 in suspension, an elongated guiding slot 22, and a lower projecting bracket 23 carrying a detent 24. The rear wall 10 of the receptacle 7 carries a pin 25 which projects into slot 22, whereby upon withdrawal of the receptacle from the container 16 said pin abuts against the terminal 26 of slot 22

and in this manner prevents their separation. Upon lifting or shifting the receptacle 7 back fully into its container 16, in the position shown in Figs. 1, 2, the extreme edge 27 of its extension 14 falls beyond the detent 24, which prevents accidental lowering or withdrawal of the receptacle 7 out of the container 16, the resiliency of the Celluloid or similar material out of which the parts are made permitting the passing of the receptacle wall 10 past the detent 24 and the 10 springing back of the latter against the edge 27 to lock the receptacle in operative state.

When it is desired to use the device, the receptacle 7 is withdrawn from its container, by pulling downwardly upon its end 11, then the brush head 4 is inserted thereinto as above described, and then the receptacle with the brush-head contained therein is slid back upwardly into its container 16 in the locked position shown. Thereafter, the removal of the brush from the retainer is effected by merely pulling downwardly upon its handle 3, which slides the receptacle 7 outwardly therewith, and the tooth brush may be merely lifted laterally out from the receptacle.

According to the modification shown in Fig. 5, 25 the side wall 17 of container 16 does not extend into alignment with the rear wall 10 of receptacle 7, but the securing bracket 21a bends away therefrom into alignment with the wall 10, so that when said bracket is secured against any 30 vertical plane surface the receptacle 7 may be slid into and out of the container 16 in the manner recited in connection with Figs. 1, 2. The front wall 18 of this container is provided with a guiding slot 22 into which projects a retention pin 25 35 depending from end wall 9 of the receptacle, and said wall also has a bracket 28 carrying a detent 29 for releasably locking the receptacle 7 in operative place.

In Fig. 6 is shown a plurality of containers 16, 40 secured to or forming part of a general suspension plate 30, thereby providing a retainer for a plurality of tooth brushes cooperating with receptacles 7 which slide into and out of the containers.

Variations may be resorted to within the scope of the invention, and portions of the improvements may be used without others.

Having thus described our invention, we claim:

A tooth brush retainer having the combination 50 of a receptacle adapted to receive the back and head of the brush when it is disposed therein in a direction transversely of its length, the end of the receptacle having means adapted to engage the sides of the brush handle to retain the brush 55

against removal therefrom in a longitudinal direction, a container for said receptacle, said receptacle being slideable longitudinally into and out of said container, a detent on the container to hold said receptacle against sliding out of said container, means to hold said receptacle to said container when it is slid out therefrom, and

means to maintain said container in suspension whereby drawing downwardly of said brush will slide out said receptacle therefrom for removal of the brush from it.
